UNITED STATES PATENT OFFICE

2,443,685

PLATE SHEARING MACHINE

Eyvind Lyche, Goteborg, Sweden

Application February 5, 1946, Serial No. 645,599
In Sweden February 10, 1945

2 Claims. (Cl. 164—47)

1

This invention relates to plate shearing machines of the kind comprising a bearing frame substantially in the form of a horizontally disposed U, carrying at the extremity of its upper leg a vertically reciprocating holder for a cutting tool adapted to co-operate with a cutting tool mounted at the extremity of the lower leg. The invention further relates to machines of the above type in which an electric motor is mounted on the top leg of the frame with its rotary axis substantially horizontal, said motor driving a connecting rod through an eccentric device, and said connecting rod imparting the necessary reciprocation to the tool through a suitable link system.

The invention has for its primary object the provision of a shearing machine of the type above referred to in which the tool holder may quickly and easily be raised so as to permit the ready insertion between the tools of the plate to be treated. The invention also has for its object to bring about various other adjustments as will hereinafter appear.

Briefly stated, the objects of the invention are met by mounting the cutting tool operating motor of the plate shearing machine with its axis of rotation parallel to a plane intermediate of the upper and lower leg of the machine frame and upon a member which is rotatably mounted eccentrically in relation to said axis of the motor for angular adjustment thereof. Thus by turning the motor carrying member through various angles as will be more fully described herein-after the tool holder can be raised for the insertion of the plate to be treated between the cutting tools or the length of the stroke of the tool holder and the tool varied.

Further, the motor has a connecting rod eccentrically connected to the shaft thereof for being reciprocated and operating one of the cutting tools through a linkage system. Thus by selecting various angular positions of the motor carrying member the movement of the tool for each rotation of the motor shaft can be changed to obtain a double cutting stroke, two equal double strokes, two unequal double strokes or one double stroke, but with the tools spaced apart for the insertion of a plate therebetween.

In the accompanying drawings an embodiment of the invention is shown by way of example, and in said drawings:

Figure 1 is a side view of a plate shearing machine according to the invention;

Figure 2 an end view of the machine;

Figure 3 a top view of the same;

Figure 4 is an enlarged vertical section through

the driving mechanism of the machine taken along the line IV—IV of Figure 2;

Figure 5 is a front view of Figure 4 as seen in the direction of the arrows V—V in Figure 3 and is partly in section to show details thereof; and

Figures 6, 7, 8 and 9 are side diagrammatic views of the cutting tool driving members in various working positions thereof with the eccentrically mounted members in cross section. Figures 6a, 7a, 8a and 9a are front elevations of the eccentrically mounted members in various positions corresponding to Figures 6, 7, 8, and 9, respectively.

10 The frame of the machine is formed by a vertical flat box 1 having the shape of a horizontally disposed U, the top leg of which is designated by the numeral 2 and the lower leg by 3. The horizontal space between the legs 2 and 3 is designated by 4. At the extremity of the top leg 2 of the frame there is fixed a box-shaped housing 6 having at its top a cylindrical portion 5. The open front side of the housing 6 is covered by a removable plate 7. In an annular recess 8 at 15 the one end of said cylindrical portion 5, the geometrical center line of which is horizontal and positioned in the middle plane of the frame, there is rotatably mounted a ring 9 which is kept in the recess 8 by means of a ring 10 fixed to the end edge of the cylindrical portion 5. To said rotatably mounted ring 9 the flange 11 of an electric motor 12 is fixed in such a manner that the motor shaft 13, which projects into the cylindrical portion 5 and which is parallel to the 20 geometrical axis of said cylindrical portion 5, is eccentrically disposed in relation to the axis of revolution of the motor carrying ring 9. On the motor shaft 13 there is fixed a fly wheel 14 the hub of which is formed as an eccentric 25 15 on which the ring-shaped end 11 of a connecting rod 18 is journaled by means of a ball bearing 16. The other forked end 19 of the connecting rod 18 is connected by means of a universal joint 19a, 19b to the laterally projecting arm 20 of a two-armed lever 21 which 30 35 40 45 50 55 is swingably mounted on a shaft 22 carried by the walls of the housing 6 and perpendicular to the middle plane of the frame 1. The downwardly projecting arm 23 of the lever 21 is connected by means of a pin 24 to the upper end of a link 25 the lower end of which is, by means of a pin 26, swingably connected to the upper end of the a holder 28 for a cutting tool 29, which holder 28 is vertically slidable in a guiding mem-

ber 27. The housing 6 may suitably be filled with lubricating oil.

The cutting tool 29 co-operates in known manner with another cutting tool 30 provided at the extremity of the lower leg 3 of the frame 1.

To the motor carrying ring 9 there is fixed a hand lever 32 projecting through a peripheral slot 31 in the cylindrical housing portion 5 and by means of which the ring 9 may be rotated to various positions as desired. At the periphery of the ring 9 there is provided a series of recesses 33 and in the wall of the cylindrical housing portion 5 there is radially slidable a pin 35 actuated by a spring 34 and adapted to co-operate with said recesses 33 so as to retain the motor carrying ring 9 in different positions. The recesses 33 and the inner end of the pin 35 co-operating with said recesses are so formed that at a turning stress of a certain degree on the ring 9 the pin 35 is automatically brought out of engagement with the recesses 33 so that the ring 9 can be turned.

It will be appreciated that by turning the ring 9 by means of the hand lever 32 to the position shown in Fig. 9 by reason of the eccentricity of the axis of revolution of the ring 9 in relation to the motor shaft 13, the lever 21 will be swung in such a manner that the tool holder 28 raises the tool 29 from the tool 30, so as to enable the plate to be cut to be inserted between the tools if the cutting of the plate is to be begun at a distance from the edge of the plate. The eccentricity of the axis of revolution of the ring 9 in relation to the axis of rotation of the motor and the eccentricity of the ring-shaped portion 17 of the connecting rod 18 in relation to the motor shaft 13 are so chosen in relation to each other and to the link system 21, 25 transmitting the movements of the connecting rod 18 to the tool holder 28 that as the motor carrying ring 9 occupies the position as shown in Fig. 6 which is a turn of about 135° for hand lever 32 and ring 9 from the position shown in Fig. 9 the lever 23, when the motor is working, has imparted to it a swinging movement between the two end positions shown by dotted lines in Figure 6 and positioned on each side of the middle position occupied by the lever 21 in Figure 4. In such a position of the ring 9 the tool holder 28 will for each revolution of the motor have imparted to it two consecutive double strokes of a comparatively short length. In the position of the motor carrying ring 9 as shown in Fig. 7, which is a turn of about 105° for lever 32 and ring 9 from the position shown in Fig. 6, the lever 21 will have imparted to it a swinging movement between the two end positions shown by dotted lines in Figure 7, whereby the tool holder 28 will for each revolution of the motor have imparted to it only one double stroke. A movement of lever 32 and ring 9 to the position shown in Fig. 8 which is a

turn of about 60° from the position of Fig. 6 will cause the tool holder 28 to be given two unequal double strokes per revolution of the motor shaft 13. By choosing the one or the other of these positions of the ring 9 or a position therebetween the movements of the tool 29 may be adjusted according to the nature of the plate to be cut by the machine.

The ring 9 is held at the various positions from that shown in Fig. 6 to the position of Fig. 9 and intermediate points by the pin 35 being inserted by spring 34 into the appropriate recess 33 for each position whereby the machine will operate with the type of stroke selected until changed by movement of lever 32.

What I claim is:

1. A plate shearing machine of the type which comprises a bearing frame substantially in the form of a horizontally disposed U carrying at the extremity of its upper leg a vertically reciprocating holder for a cutting tool adapted to co-operate with a cutting tool mounted at the extremity of the lower leg, and in which an electric motor is mounted on the top leg of the frame with its rotatory axis substantially horizontal, said motor driving a connecting rod through an eccentric device, and said connecting rod imparting the necessary reciprocation to the tool holder through a suitable link system, characterized in that the motor, the axis of rotation of which is parallel to the middle plane of the frame of the machine is carried by a member revolvably mounted in the upper leg of the frame eccentrically in relation to the axis of rotation of the motor shaft and adjustable to different angular positions.

2. A plate shearing machine as claimed in claim 1, characterized in that the link system transmitting the movement of the connecting rod to the tool holder comprises a two-armed lever swingably mounted on a shaft perpendicular to the plane of the frame, one arm of said lever being connected by means of a universal joint to the free end of said connecting rod, while the other arm of said lever is swingably connected to one end of a link which is swingably connected by its other end to the reciprocating tool holder.
